G. A. SMYTHE.
CALCULATING SCALE BEAM.

No. 74,624.

Patented Feb. 18, 1868.

United States Patent Office.

GEORGE A. SMYTHE, OF READING, PENNSYLVANIA.

Letters Patent No. 74,624, dated February 18, 1868.

IMPROVEMENT IN CALCULATING-SCALE BEAMS.

The Schedule referred to in these Letters Patent and making part of the same.

TO ALL WHOM IT MAY CONCERN:

Be it known that I, GEORGE A. SMYTHE, of Reading, in the county of Berks, in the State of Pennsylvania, have invented a new and useful Improvement in Weighing-Scale Beams, to be attached to counter-scales; and I do hereby declare that the following is a full, clear, and exact description of the construction and operation of the same, reference being had to the annexed drawings, making a part of this specification, in which—

Figure 1 is a perspective view of the calculating-scale beam.

Figure 2, a surface view of the scale-beam.

Figure 3, a view of the beam.

The nature of my invention consists in making a calculating scale-beam with a slide as a weight from one-hundredth part of a pound, on which the price, from ten cents to one dollar, is arranged, corresponding with lines on the cylinder, and designating, as it is moved along, any amount, from one cent's worth to one pound, at any price on said slide. The sixteen-cent line, as marked on the slide, I have divided into fractions of an ounce; so the scale, if used independent of the prices, will give the fractional parts of a pound and ounce, also telling what such fractional part amounts to in money, at any price on said slide.

To enable others skilled in the art to make and use my improvement, I will proceed to describe its construction and operation.

I construct my calculating-beam and slide as shown in fig. 1. In the construction, I take a metallic plate of the dimensions required, first provided with a steel die, when the impression is taken at one stamp of the die. The plate is then bent in a machine and fixed upon the cylinder A, as represented by drawing. The slide B is then put on, and the clips E at each end, which makes the cylinder complete. It is then slipped on the beam, on which it revolves, and attached to any counter-scale.

What I claim as my improvement, and desire to secure by Letters Patent, is—

The arrangement and combination of the slide B, clasping around the whole beam, marked and notched as represented in fig. 1 and fig. 2, together with the shape of the slide, and the ounce-line, marked sixteen on slide, showing the fractional parts of a pound and an ounce on the beam, and the amount in money

GEO. A. SMYTHE.
